JOHN L. LITTLE, OF ATKINSON, NEW HAMPSHIRE.

Letters Patent No. 83,646, dated November 3, 1868.

IMPROVEMENT IN STOVE-PIPE THIMBLES.

The Schedule referred to in these Letters Patent and making part of the same.

To all whom it may concern:

Be it known that I, JOHN L. LITTLE, of Atkinson, county of Rockingham, and State of New Hampshire, have invented a new and useful Improvement in Stove-Pipe Thimbles and Collars; and I do declare that the following is a full, clear, and exact description of the same, reference being had to the annexed drawings, forming a part of this specification, in which, in

Figure 1, A represents a perspective view of my improved stove-pipe thimble and collar.

Figure 2 is a perspective view of my improved collar, showing rim R furnished with T-shaped slots, S S.

Figure 3 represents a front view of ventilating-cover.

Figure 4 represents a full-size sectional view of my entire device, the line a a, fig. 1, indicating plane of section.

Similar letters of reference in the several figures indicate corresponding parts.

The object and purpose of this invention are to furnish a cheap and efficient stove-pipe thimble, whereby stove-pipes of various sizes may be safely conducted, not only into brick chimneys, but also through partitions wholly of wood, when necessary, and also to furnish, when desired, a convenient and effective ventilator for the apartment in which it is used.

And it consists of a stove-pipe thimble, with the parts constructed in such way as that several sizes of stove-pipes may be used in the same thimble by the removal and insertion of different collars, having different-sized openings for the stove-pipe.

To enable those skilled in the arts to make and use my invention, I will now proceed to describe it.

The cylinder, A, fig. 1, is made of cast-iron, one-eighth of an inch in thickness, six and a half inches interior diameter, and from four to six inches in length, and furnished with projections P P, shown in fig. 4.

Collar C, fig. 2, is constructed with a projecting rim, R, of about three-eighths of an inch in depth, the outside diameter of said rim corresponding to the inside diameter of cylinder A A, fig. 4. When the collar C is applied to the cylinder A A, as shown in figs. 1

and 4, the slots S S, in rim R, fig. 2, allow the passage of projections P P, fig. 4, until the collar is brought home against the end of the cylinder, then a slight turn in either direction secures the collar firmly in its place.

The interior diameter of collar C C being always less than the interior diameter of cylinder A A, there will always be more or less air-space between the heated stove-pipe F F and the interior of the thimble, thus preventing the communication of heat from the stove-pipe to the partition.

Fig. 3 is a front view of a cover, furnished with a T-slotted rim, as shown in fig. 2, and also with a ventilating-register, V, to be used, when the stove is removed, in place of the ordinary cover, when it is desirable to ventilate the apartment in which it is used.

Fig. 4 is a horizontal sectional view of my improved thimble and collar, full size, the line a a, fig. 1, indicating plane of section. A A are the cylinder, with the inward projections P P, which serve to confine collar C C in its proper place; R R, slotted rim; F F, five-inch stove-pipe. The air-spaces, brick and wood surroundings, are indicated by words on the drawing.

I am aware that chimneys are made in sections, which sections are secured and held in place by means of what is termed a "bayonet-catch." I am also aware that such device is extensively used in attaching the bottoms of lanterns to their tops. Such construction of means for holding two sections of cylinder together I do not claim, as I limit my invention to the construction of, and its adaptation to stove-pipe thimbles.

Having thus fully described my invention, What I claim, and desire to secure by Letters Patent, is—

A stove-pipe thimble, composed of cylinder A, having the inward projections P, removable collar C, with rim R and slot S, all constructed and operating in the manner and for the purpose described.

JOHN L. LITTLE.
